No. 823,032.

PATENTED JUNE 12, 1906.

W. A. CARDY.
BOX COVERING MACHINE.
APPLICATION FILED FEB. 18, 1905.

WITNESSES:

UNITED STATES PATENT OFFICE.

WILLIAM A. CARDY, OF CHELSEA, MASSACHUSETTS, ASSIGNOR TO THE STOKES AND SMITH COMPANY, OF PHILADELPHIA, PENNSYLVANIA, A CORPORATION OF NEW JERSEY.

BOX-COVERING MACHINE.

No. 823,032.

Specification of Letters Patent.

Patented June 12, 1906.

Application filed February 18, 1906. Serial No. 246,302.

To all whom it may concern:

Be it known that I, WILLIAM A. CARDY, a citizen of the United States, residing at Chelsea, in the county of Suffolk, State of Massachusetts, have invented certain new and useful Improvements in Box-Covering Machines, of which the following is a specification.

My invention relates to box-covering machines, and has for an object to provide a machine for covering flanged, polygonal-shaped boxes.

Other and further objects will appear in the following description and will be more particularly pointed out in the appended claims.

In the drawings, Figure 1 is a vertical section of a form-block, its immediately-associated parts, and the presser-rollers. Fig. 2 is a detail sectional view. Fig. 3 is a perspective view showing one of the presser-rollers, and Fig. 4 is a detail sectional view of the block 6.

1 represents the spindle-plunger, upon the lower end of which is mounted a suitable vertically-movable form-block 2, adapted to enter a polygonal-shaped box 3 and forming part of the box-receiving means. The other member of the box-receiving means comprises a wooden block 5, mounted upon the upper end of a lower upright spindle 4 and having suitably secured thereto an iron polygonal-shaped base 6, provided with lateral projections 7 on all sides, the base being co-extensive with the bottom and the flange of the box and extending beyond the edges of the form-block. The under faces of these projections are constructed with undercuts 8 to provide portions or points 9 to engage the covering-pressing means, to be herein-after described, and cause said means to traverse the side walls of the box.

The covering-pressing means comprises a number of rollers 10, positioned to operate simultaneously on various sides of the box and each rotatably mounted at its ends 13 in bearing projections 14 and having a portion to enter the angle formed by the flange and a side wall, and a rounded portion, such as the periphery, to roll on a side wall, and thus press the covering on the box. To provide these portions, each roller is cut away to pro-

vide a recess 11, extending longitudinally of the axis of the roller and in which is placed a strengthening-strip 12. One wall of the recess forms a longitudinal offset or edge 18 to enter the angle formed by the flange 19 and a side wall of the box, and the other wall of the recess forms a longitudinal abutment for a co-operating point or edge 9 on the box-receiving means.

Extending from the machine is a rod or arm 15, to the free end of which is secured one end of a spiral spring 16, the other end of the spring being secured by screw 17 to the end 13 of the roller. This spring forms automatic means for moving the roller in a direction opposite to that in which it is moved by the box-receiving means.

I have shown but two presser-rollers in my drawings; but of course it will be understood that there are as many as there are side walls on the box and that each presser-roller of the machine will be like those shown herein.

The operation of the machine is as follows: The parts being assembled in the position shown in Fig. 1 and after the box-blank has been placed in position on the base 6, the machine is started and the plunger carrying the form-block is by suitable mechanism forced down. In its downward course it depresses the block 5 and the base 6 and the teeth or projections 9 engage with the wall of the recesses 11 in the rollers 10, whereby said presser-rollers are revolved, thus bringing the edges 18 of the rollers squarely in the corners of the box formed by the flange 19 and the walls of the box, as shown in Fig. 2. In the continued motion of the machine the rollers press the cover snugly on the flange and in the exterior angles of the box and then roll upon the sides of the box. When the box-receiving means is elevated, the rollers automatically return to normal positions under the action of the coil-spring 16.

Having thus described my invention, what I claim, and desire to secure by Letters Patent, is—

1. In a machine for covering flanged boxes, a box-receiving means and a plurality of rotatably-mounted covering-pressing rollers arranged to operate simultaneously on various sides of the box and each provided with a recess extending longitudinally of its axis to

form portions engaging the wall of the box and the flange.

2. In a machine for covering flanged boxes, a rotatably-mounted covering-pressing member, having a portion adapted to press the paper on the side wall of the box, and a recess extending longitudinally of the axis of the member to receive the flange of the box.

3. In a machine for covering boxes, a rotatably-mounted cover-pressing member adapted to roll in contact with the side wall of the box to press the paper thereto and having a recess extending longitudinally of the axis of the member to receive a flange on the box; said recess forming an offset which presses the paper into the angle caused by the flange.

4. In a machine for covering boxes, a rotatably-mounted cover-pressing member adapted to roll in contact with the side wall of the box to press the paper thereto and having a recess extending longitudinally of the axis of the member to receive a flange on the box; said recess forming an offset which presses the paper into the angle caused by the flange, and forming with the periphery of said member, a part which projects into the angle between the flange and side.

5. In a box-covering machine, a cover-pressing means, and a box-receiving means, movable relatively to one another and constructed to cause the pressing means to traverse the wall of the box; said cover-pressing means being engaged by the box-receiving means in the relative movement of the parts and having an offset conforming to an angular portion of the box, said offset entering the angular portion of the box when the parts are engaged.

6. In a box-covering machine the combination of the moving box-receiving member, and the rotary cover-pressing member having a recess providing an offset conforming to an angular portion of the box, and also providing an offset constructed to be engaged by the box-receiving member to cause the cover-pressing member to enter such angular portion of the box.

7. The combination with a form-block of a box-covering machine, of a pressing-roller provided with portions constructed to engage a flange on a box, means moved with the said block to impart movement to the roller in one direction, and means automatically moving the roller in the other direction when the direction of movement of the form-block is changed.

8. The combination with a form-block of a box-covering machine, of a pressing-roller provided with portions constructed to engage a flange on a box, means moved with the said block to impart movement to the roller in one direction, and a spring moving it in the other direction.

65 9. The combination with a box-receiving

means, of a covering-pressing roller having portions extending longitudinally of its axis and adapted to receive a flange on a box and to enter the angle between the flange and a side wall of the box.

10. The combination with a box-receiving means, of a covering-pressing roller having a recess extending longitudinally of its axis and constructed to receive a flange on the box, an edge adapted to enter the angle formed between the flange and the side wall, and a rounded portion for movement on a side wall of the box.

11. The combination of a box-covering roller having a recess positioned to receive a flange on a box, a form-block and means moved with the form-block and adapted to enter the recess and cause the movement of the roller.

12. The combination with a base on which the box is supported, of pressing-rollers constructed to receive a flange on a box and means carried by said base to impart movement to the rollers.

13. The combination with the form-block, of a base-block extending beyond the edges of the form-block, a roller provided with a recess one wall of which provides an edge adapted to enter the angle formed between a flange on a box and a side wall, means on the base engaging the roller to cause its movement in one direction and means automatically moving the roller in the other direction.

14. In a machine for covering flanged boxes, a box-receiving means and covering-pressing means, independently mounted and movable relatively to one another, the parts being provided with portions constructed to engage during the relative movement and cause the cover-pressing means to operate on the box; and the covering-pressing means being provided with portions constructed to operate upon a side wall and a flange on the box to press the covering thereon.

15. The combination with a form-block adapted to fit within the box, of a base co-extensive with the bottom of the box and the flange thereof and upon which the box rests, and rollers recessed to receive the flange of the box and adapted to press a covering on the flange and the side walls of the box.

16. The combination with a form-block adapted to fit within the box, of a base co-extensive with the bottom of the box and the flange thereof, and upon which the box rests, covering-pressing means provided with portions adapted to contact with a wall of the box and with the flange and co-operating means on the covering-pressing means and the base, whereby when the parts are moved relatively to one another, the covering-pressing means is caused to act on the box and its flange.

17. The combination with a form-block adapted to fit within the box, of a base co-

- extensive with the bottom of the box and the flange thereof and upon which the box rests, rollers recessed to receive the flange of the box and adapted to press a covering on the flange and the side walls of the box, and projections on the base adapted to engage the rollers and cause them to set on the box during a relative movement of the parts. 5
18. The combination with a form-block adapted to fit within the box, of a base coextensive with the bottom of the box and the flange thereof and upon which the box rests, rollers recessed to receive the flange of the box and adapted to press a covering on the flange and the side walls of the box, projections on the base adapted to engage the rollers and cause them to act on the box during a relative movement of the parts, and means for automatically returning the roller to its original position. 10
19. The combination with a form-block constructed to fit within a box, of a base coextensive with the flange on the box, and pressing means supported independently of the base and constructed to enter the angle of the box between the flange and a side wall. 15
20. The combination with a form-block adapted to fit within a box, of a base coextensive with the bottom of the box and the flange thereof, and upon which the box rests, and covering-pressing means supported independently of the base and provided with portions adapted to contact with a wall of the box and with the flange. 20
- 35 21. In a box-covering machine, removable means for applying a covering to side walls of a box having extension edges, comprising a roller provided with a longitudinal recess throughout its length to receive the extended edge. 25
- 40 22. In a box-covering machine, means for applying a covering to the side wall of a box having an extension edge, comprising a roller provided with a recess, means to move said roller in one direction and yielding means to return said roller to its original position. 30
- 45 23. In a box-covering machine, means for applying a covering to the side wall of a box having an extension edge, comprising a roller provided with a recess, means to rotate said roller in one direction, and means to return said roller to its original position. 35
- 50 24. In a machine for covering extension-edge boxes, a movable box-support, means for applying a covering-blank to the walls of the box, means moving in advance of said first-named means to turn the covering-blank over and down upon the extension edges, and means whereby the movement of the box-support may actuate said first and last named means. 40
25. In a machine for covering extension-edge boxes, means for covering a wall of the box, comprising a rotatable element having a longitudinal recess to receive an extended edge of the box, a wall of said recess being arranged to engage and turn the covering material over and down upon the said extended box edge, and a convex face on said element for applying the covering material to the box-wall proper. 45
26. In a machine of the class described, a roller for applying a covering-blank to the side and end walls of an extension-edge box, and provided with a concave surface for turning the covering-blank over and down upon the extension edge and a convex face for applying the covering-blank to the box-wall proper. 50
27. In a machine for covering extension-edge boxes, means for applying the covering-blank to the side and end walls of the box, comprising a roller having a concave and a convex surface, and means intermittently engaging said concave surface to partially rotate said roller. 55
28. In a machine for covering extension-edge boxes, means to support the box, means for applying the covering-blank to the walls of the box, comprising a roller having a longitudinal recess, and means on the box-support to engage a wall of the recess to partially rotate said roller. 60
29. In a machine for covering extension-edge boxes, means to support the box, means for applying the covering-blank to the walls of the box, comprising a roller having a concave and a convex surface, and means on the box-support to engage the concave surface. 65
30. In a box-covering machine of the class described, an element having a convex face for applying the covering material to a vertical wall of a box, and means associated with said element for turning the covering material over an extension edge of the box. 70
- 35 31. In a box-covering machine of the character described, opposed rollers for applying the covering material to the opposite vertical walls of a box, and means associated with said rollers for turning the covering material over the extension edges of the box. 75
- The foregoing specification signed at Washington, District of Columbia, this 9th day of February, 1905.
